UNITED STATES PATENT OFFICE.

CARL G. G. BERGSTROM, OF ST. PAUL, MINNESOTA.

BAG-HOLDER.

1,271,653.

Specification of Letters Patent.

Patented July 9, 1918.

Application filed August 31, 1916. Serial No. 117,822.

To all whom it may concern:

Be it known that I, CARL G. G. BERGSTROM, a citizen of the United States, residing at St. Paul, in the county of Ramsey 5 and State of Minnesota, have invented a new and useful Improvement in Bag-Holders, of which the following is a specification.

This invention relates to certain new and useful improvements in holders for sacks 10 and is particularly designed to engage and retain the mouth of the sack or bag in distended or in open position, so that it may be most conveniently filled and packed with grain, articles or produce of whatever nature; and as such includes features of improvement over the construction illustrated 15 and described in my Patent Number 1,230,-060, granted to me on the 12th day of June, 1917, for bag holders.

20 One of the improved features of the present invention is the provision of novel means whereby the bag holding elements may be initially positioned or adjusted to approximately the size of the mouth of the sack or 25 bag to be filled. Another object is to provide means for engaging the mouth of the bag so that the same may be quickly attached about the bag-holding elements and in such manner that the tension about the 30 bag mouth is evenly distributed so as to most effectively extend it for filling and to minimize the likelihood of ripping or tearing 35 of the bag.

A further object is to provide a novel 40 means of mounting the bag engaging devices so as to avoid the possibility of personal injury to the operator or damage to the goods being put into the bag.

Other and further objects and advantages 45 of the invention will be hereinafter set forth and the novel features thereof defined by the appended claim.

In the drawings, Figure 1 is a side elevation 50 of the invention showing a bag in filling position held thereby; Fig. 2 is a partial section taken on the line X—X of Fig. 1 looking in the direction of the arrow, showing the bag holding elements in slightly further extended position than as illustrated in Fig. 1; Fig. 3 is an enlarged section taken 55 on the line Y—Y of Fig. 2, showing the housing and bearing, the latter in dotted lines, for one of the bag engaging members, and Fig. 4 is a detail, partly in section and broken away, of a portion of the carriage

mechanism supporting the movable bag holding element.

Like numerals of reference refer to like parts in the several figures of the drawings.

In the drawing illustrating this invention, 60 the reference character A represents a base or platform upon which is mounted a standard B comprising a support 10 rigidly secured in any desired manner to the base, and a tubular or other shaped member 11 telescoping and longitudinally movable upon the said support. These parts are fully set forth in my copending application, Serial Number 93,071, filed April 24, 1916; but for the purposes of this application, certain of 70 the specific features of construction of said parts will be here described.

The tubular member 11 is formed of two sections 12 and 13, the upper extremity of the section 12 being enlarged as shown at 75 14 to receive for securance in any preferred method, the lower extremity of the section 13. Pivotaly secured between a pair of outstanding lugs 15 (only one of which is shown) is a dog 16 held in engagement with 80 longitudinal waved serrations 17 formed on the support 10 as fully described in my copending application above referred to. By this means the member 11 may be moved vertically upon the support 10 and retained 85 in selective position as and when desired.

Attached about the section 13 of the member 11 is a collar 18 from which extend one or more arms 19 supporting at their outer free ends a bag holding element 20 made of 90 any suitable material and configuration, though here shown of segmental contour. At each of its opposite ends, the element 20 terminates in an outstanding portion 21 having an aperture through which a tubular member 22 is adapted to slide for a purpose which will later appear. Telescoping within each of the members 22 is an elongated rod 23, to the outer free ends of which rods are secured the outstanding portions 24 of a 100 second bag holding element 25 here shown as similar in construction and shape as the element 20 above described. It is to be understood that the segmental contours of the elements 20 and 25 extend in opposite directions. At their corresponding ends, the members 22 are each provided with a threaded opening, through which a setscrew 26 operates to bind upon and hold the rods 23 in different extended positions. 105 110

Upon the concave adjacent faces of the elements 20 and 25 and at spaced intervals along their respective lengths are secured, fixedly or otherwise, enlargements 27 which are preferably though not essentially of inverted semi-cone shape, upon the lower face of each of which is suitably journaled, as by means of a threaded bolt 28, (see Fig. 3), a toothed wheel 29 adapted to revolve 10 in a substantially horizontal plane and to retain in position thereon a portion of the mouth of the bag or sack to be filled. While it is necessary that the teeth of the wheels 29 project a sufficient distance beyond the 15 outer convex faces of the elements 20 and 25 to engage and hold the bag, it is equally necessary that the portion of the wheels which extends inwardly, be protected from clogging by small grain, or other articles 20 deposited in the bag, and to eliminate possibility of personal injury to the operator or damage to the goods being put into the bag. For this purpose, the enlargements 27 are provided, it being understood that at their 25 base, the enlargements are of sufficient size to entirely cover the inwardly extending portions of the wheels. By forming the enlargements of inverted semi-cone shape, there is no possibility of the retention thereon of any of the produce being put into the bag.

At their free ends each of the tubular members 22 is pivotally attached to the end of the long arm 30 of a bell crank, the angle 35 portion of which is journaled between two lugs 31 (only one being shown) extending outwardly from a yoke 32 having integral projections 33 suitably engaging the support 10 for reciprocable movement thereon. The 40 yoke 32 also has a projection 34 to which one end of a spring 35 is secured, the other end of the spring being attached to the end of the short arm 36 of the bell crank. By the construction just described, the tension of 45 the spring 35 will cause the element 25 to move forcibly away from the stationary element 20. As more fully set forth in my co-pending application, the apparatus includes evener rods 37 (only one being here shown) 50 pivoted at one end to the collar 18 carried by the tubular section 13 and the other end to the long arm 30 of the bell crank, the object of such evener rods being to effect an even up or down movement to the yoke 32 when the movable bag element and its 55 supporting or carriage mechanism is moved in toward or away from the stationary bag element and to thus eliminate any binding tendency of the parts in their several movements.

My invention is well adapted to support bags of any size with their mouths in extended position for filling. The first step in the successful operation of the device, however, is to manually adjust the "at-rest" 65 position of the bag elements with respect to one another to approximately conform to the size of the particular bag opening. This may be done by loosening the set screws 26 and moving the rods 23 one way or the other 70 into the tubular members 22. After this is done, and the set screws retightened, the bag element 25 is forced inwardly against the tension of the spring 35 a sufficient distance to enable the bag mouth to be secured 75 about the several wheels 29 on both the elements when the force against the element 25 is removed and such element thrown outwardly by the action of spring 35 so as to securely retain the mouth of the bag opened. 80 By employing rotatable devices such as 29, it will be understood that the tension about the bag mouth is evenly distributed, so that there is no sagging of the bag or any likelihood of its being ripped or torn. 85

In accordance with the patent statutes, I have described the principles of operation of my invention, together with the apparatus which I now consider to represent the best embodiment thereof, but I desire to have it understood that the construction shown is only illustrative, and that the invention can be carried out by other means and applied to uses other than those above set forth within the scope of the following 90 claim. 95

Having described my invention, what I claim as new and desire to protect by Letters Patent is:

A bag holder, comprising, in combination, 100 a standard, a plurality of bag holding elements supported by said standard, one of said elements being movable away from the other, and both of said elements being flat upstanding bands of segmental contour extending in opposite directions, and a series of closely placed freely rotatable bag engaging elements journaled on the lower edge of each and projecting inwardly and outwardly from the concave and convex sides of said 105 bands to tensionally engage and retain in curved open position the mouth of a bag and to evenly distribute the tension about the bag mouth, said bands being formed with guides over the instanding portion of 110 each rotatable bag engaging element. 115

In testimony whereof, I have signed my name to this specification.

CARL G. G. BERGSTROM.
